UNITED STATES PATENT OFFICE.

HARRY O. SHUNK, OF DENVER, COLORADO.

DESIGN FOR A CIGAR AND CIGARETTE HOLDER.

42,092.

Specification for Design.

Patented Jan. 9, 1912.

Application filed July 17, 1911. Serial No. 639,027. Term of patent 3½ years.

To all whom it may concern:

Be it known that I, HARRY O. SHUNK, a citizen of the United States, residing in the city and county of Denver and State of Colorado, have invented a new, original, and ornamental Design for Cigar and Cigarette Holders, of which the following is a specification, reference being had to the accompanying drawing, forming a part thereof.

The figure of the drawing is a side elevation of a cigar and cigarette holder showing my new design.

I claim:

The ornamental design for a cigar and cigarette holder, as shown.

In testimony whereof I affix my signature in presence of two witnesses.

HARRY O. SHUNK.

Witnesses:

OTTO E. HODDICK,
